RALPH W. HILTON, OF WICHITA, KANSAS, ASSIGNOR OF ONE-HALF TO HARVEY W. BROWN, OF WICHITA, KANSAS

WING SPAR FOR AEROPLANES

Application filed January 2, 1930. Serial No. 418,081.

This invention relates to improvements in spars for aeroplane wings of the cantilever type and one of the objects of the present invention is to provide a cantilever wing which will be substantial in construction and will require no struts or bracings on the exterior of the wing and which struts or braces reduce the speed of travel of the aeroplane due to the resistance offered to the wind, and such wings, as are ordinarily constructed, being required to be made comparatively small in area, whereas the wing of the present invention may be made of greater area, and as stated, without the necessity of employing struts or braces.

Another object of the invention is to provide an aeroplane wing of the cantilever type within which there is arranged a novel strut construction which extends from tip to tip of the wing and which structure has its component elements connected throughout its entire extent, so as to obviate the employment of any braces or the like which would retard the speed of travel of the aeroplane.

Another object of the invention is to provide a strut constituting an integral whole, the strut being provided in its intermediate portion with a bend adapting this portion to extend through the cabin of the aeroplane and thus obviate the necessity of providing attaching means upon the sides of the aeroplane body for the attachment of separate struts, where the integral structure of the present invention is lacking.

Another object of the invention is to provide a strut of the class described which may be manufactured of metal or of wooden or other non-metallic parts, as may be desired.

This invention also consists in certain other features of construction and in the combination and arrangement of the several parts, to be hereinafter fully described, illustrated in the accompanying drawings, and specifically pointed out in the appended claim.

In describing my invention in detail, reference will be had to the accompanying drawings wherein like characters denote like or corresponding parts throughout the several views, and in which:—

Figure 1 is a schematic top plan view of a cantilever wing constructed in accordance with the invention.

Figure 2 is a view in front elevation of the wing structure illustrating the manner in which the bend is formed therein, this view also illustrating, schematically, the cross sectional contour of the wing at different points in its length.

Figure 3 is a vertical front to rear sectional view through the wing of this embodiment of the invention, taken substantially on the line 3—3 of Figure 2 looking in the direction indicated by the arrows.

Figure 4 is a sectional view illustrating the manner in which the bend in the intermediate portion of the strut structure is arranged within the cabin of the aeroplane.

Figure 5 is a view similar to Figure 1 illustrating, in top plan, a wing constructed of wood.

Figure 6 is a view similar to Figure 2 illustrating the structure shown in Figure 5, schematically.

Figure 7 is a vertical front to rear sectional view on the line 7—7 of Figure 6 looking in the direction indicated by the arrows.

In the embodiment of the invention illustrated in Figures 1 to 4 inclusive, the wings of the aeroplane are indicated by the numeral 1 and the cabin by the numeral 2, and the wings are made of any material usually employed for the purpose, and the spar, in this embodiment, being formed from lengths, preferably of tubular piping. The strut comprises two wing sections which are indicated in general by the numeral 3 and which are constructed and housed within the hollow wings, 1, and each of the struts comprise upper and lower bars 4 and 5 respectively. As shown in Figure 3, there are two of the upper bars 4 and a single one of the lower bars 5, and vertical bracing bars 6 extend between the bars 4 and the bars 5, and are welded at their ends to these bars, and two alternate ones of the bars 6, indicated specifically by the numeral 7, being preferably arranged in a diagonal position as clearly shown in Figures 2 and 4 of the drawings.

These bars are likewise welded at their ends.

ends at the points of connection of the respective bars 6 with the bars 4 and 5. The bars 6 and 7 are of gradually decreasing length formed from the inner portions of the wing spar to the ends thereof and, as shown in Figure 4, the portions of the spar extend laterally from the intermediate portion and are completely housed within the respective wings 1.

At the intermediate portion of the spar, the bars referred to above are bent so as to provide a downwardly bent intermediate portion indicated by the numeral 8 and the downwardly and inwardly extending parts of the structure which constitute this portion are located in the cabin 2 of the aeroplane, as shown in Figure 4, and preferably, at such points as may be desired, in the length of the structure, and top cross bars 9 may be arranged to extend between the upper cross bars as shown in Figure 3 of the drawings.

Instead of a tube, the component parts of the structure above described may be made of sheet metal bent into hollow box form, or U-shaped or V-shaped and at all points where the component parts, of the structure, embodying the invention intersect the longérons of the body or fuselage structure, the said parts are welded to the said longérons so that the structure is mounted in a very secure manner.

Figures 5, 6 and 7 of the drawings illustrate that the spar structure may be of wood and as most clearly shown in Figure 7 of the drawings, the spars, which are indicated by the numeral 10, may be of substantially V-form in cross section as shown in this figure and are made up of a plurality of plies 11 of wood which are assembled with the grains running in different directions in relatively adjacent plies, the plies being of course united at their contacting surfaces by any suitable adhesive medium so that the structure is practically an integral one and possesses great strength and is capable of resisting considerable strains, and yet sufficiently light in weight to render it highly suitable for use in accordance with the principles of the invention. It will be observed by reference to Figure 4 of the drawings, that in both embodiments of the invention the wing spar of the invention will be arranged, at its intermediate portion, in the cabin of the fuselage, in such a manner as to leave sufficient room for passengers and at the same time permit of the wing being disposed on the thrust line of the aeroplane, or in other words the straight line between the center of the propeller hub and the tail, of the aeroplane, so that the wing is of the mid-wing type and constitutes a cantilever wing.

What I claim is:—

In an aeroplane, the combination with the fuselage and a mid-wing extending from op-

posite sides thereof, of a spar structure wholly erected, at its oppositely extending side portions in the wing, and, at its intermediate portion, in the fuselage, the said spar structure comprising substantially horizontal upper bars arranged in the upper portions of the wings and converging toward each other toward the tip ends of the wing, the said upper bars having their intermediate portions inclined downwardly, within the fuselage, from points at opposite sides of the fuselage, a lower bar arranged below the first mentioned bars and including portions inclined upwardly toward the meeting ends of the converging upper bar portions, the said lower bar including intermediate portions inclined downwardly, within the fuselage, from points at opposite sides of the fuselage, and parallel to the inclined intermediate portions of the upper bars, a plurality of braces, extending vertically between the intermediate portions of the upper and lower bars and also between the converging portions of the upper bars, and the upwardly inclined portions of the lower bars, other braces extending diagonally between the points of connection of each two relatively adjacent ones of the first mentioned braces, and braces extending between the said upper bars.

In testimony whereof I affix my signature.
RALPH W. HILTON.
